UNITED STATES PATENT OFFICE.

EUGENE E. COLLAMER AND GEORGE R. COLLAMER, OF HILTON, NEW YORK, ASSIGNEES
OF ONE-THIRD TO JOHN B. FREY COMPANY, INC., OF ROCHESTER, NEW YORK, A
CORPORATION OF NEW YORK.

BARREL-CENTERING DEVICE.

Application filed December 20, 1920. Serial No. 432,053.

To all whom it may concern:

Be it known that we, EUGENE E. COLLAMER and GEORGE R. COLLAMER, of Hilton, in the county of Monroe and State of New York, have invented certain new and useful Improvements in Barrel-Centering Devices; and we do hereby declare the following to be a full, clear, and exact description of the same, reference being had to the accompanying drawings, forming a part of the specification, and to the reference numerals marked thereon.

Our invention relates to machines for performing operations on containers or barrels, such as the heading of barrels, and especially to the means for moving the container or barrel to and from the position where operated upon for such machines. The object of our invention is to provide an improved device of the above class which shall be of simple construction, and adapted for use with either filled or empty containers to permit them to be easily and quickly moved into operative position without lifting the same, and without the exercise of care and accuracy in centering or placing such container or barrel on the machine, these guiding functions being performed automatically. To these and other ends the invention consists in certain improvements and combinations of parts, all as will be hereinafter more fully described, the novel features being pointed out in the claims at the end of the specification.

35 In the drawings:

Figure 1 is a side view partially in section of our improved barrel centering device.

Figure 2 is a section on the line 2^a—2^a of Figure 4.

Figure 3 is a section on the line 3^a—3^a of Figure 1.

Figure 4 is a side view of the container in position ready to have the cover applied thereto.

Similar reference characters throughout the several views indicate the same parts.

With our construction it is not necessary that a barrel be lifted into an inverted position, and among the essential features of the present invention may be mentioned its simplicity of construction and ease of operation, whereby the barrel or container may be correctly centered and covered with a mini-

55 mum of effort and without lifting the same regardless of whether the barrel is filled or empty.

Referring to the drawings, the numeral 10 designates a barrel or other container which, if of substantially circular cross section, may be easily rolled over the storage or loading platform 11 and onto the work holder or carrying platform 12 which is of substantially the same height as the loading platform. In Figure 1 the work holder is 60 shown resting upon the step or fixed support 13 and also upon the end roller 14 of a plurality or series of parallel wheels or rollers 15, each of which is journalled in a fixed support 16 so as to be freely rotatable. By tilting the barrel from the position shown in Figure 1, the same may be caused to rest upon a plurality of the rollers 15 and then slid over the rollers until the work or container cooperates with the guideways or work alining device 17 which, together with the stop 18, form a centering or alining yoke whereby the barrel or container is brought in proper alinement with the plunger or element 20. The outer ends 70 of the guideways 17 are preferably tapered as shown at 17^a in Figure 2, so that in case the barrel is not in proper alinement it may be guided into the position shown in Figure 2, and the guideways 17 are preferably 75 disposed somewhat above the work carrying platform 12 in order to cooperate with only the lower portion of the barrel. A suitable frame 19 is adapted to support the guideways 17 as well as some suitable fluid pressure cylinder or other means for operating the plunger 20. The lower end of the plunger 20 is enlarged as at 21 to an amount nearly the size of the cover which is to be applied to the barrel by being forced downward through the expandible cover guide 22 into the croze. The sides of the cover guide 22 are shown as being slightly tapered in order to guide the cover into place, and the same is supported on the chime of the barrel by means of the angle iron 22^a. After being forced into position, the cover may be securely retained in place by having the hoops or bands 22^b applied and tightened in place.

100 105 After having the cover applied, the barrel or container may be rolled back over the rollers 15 until the work carrying platform

2

12 cooperates with the stop or side of the storage or loading platform 11, when if the platform 12 still rests upon several of the rollers 15, it may be easily tilted a small amount to the position shown in Figure 1, in which the same is carried by the roller 14 and the step 13. The step 13 may be disposed preferably slightly more than half of the length of the work carrying platform 12 from the axis of the roller 14, in order that the barrel supporting platform may automatically cooperate with the step 13 and assume the position shown in Figure 1 without the necessity of tilting the same by hand. To prevent a rebound of the work holder and container supported thereby in case the same has sufficient momentum, the stop 18 may be made yieldable as for example by the addition of a rubber or padded surface. It will be apparent that the rollers 15 may be power driven in which event the movement of the barrel and platform from the position shown in Figure 1 to the cover press and back again may be automatic. The guide yoke 17 is adapted to correctly align only barrels of a given size, but in case containers of different size are to be used, the guide yoke 17 may be made removable from the frame 19 and another yoke inserted of appropriate size to fit the barrel used.

In the embodiment shown in Figure 1, the work carrying platform 12 is made in two portions, an upper and lower 23 and 24 respectively, one of which is mounted on rollers 25 so as to be slidable transversely of the other. In the form shown the rollers 25 are journaled in bearings 26 secured to the top portion 23 so that this upper portion may be rolled transversely of the lower. In order that the upper and lower portions may be normally in alinement, a plurality of springs are used, which may comprise leaf springs 27 secured at one end for example to the lower portion and having their other ends free and disposed in opposite directions. A pin 29 disposed between these leaf springs is secured to the other portion, in this case the upper, and in this way the upper portion may be made yieldable or resilient with regard to the lower so that when the barrel 10 is not correctly centered on the upper portion of the work holder 12 the container will, as the same is moved into the guide-ways 17, be guided by the inclined or tapering portion 17^a into the centering yoke by means of this yieldable or resilient cooperation between the upper and lower portions of the work holder 12. With the construction shown for the work holder 12, the upper portion is movable in either direction with regard to the lower, thus giving the container 10 a universal horizontal freedom of movement, and a less force is required to move the barrel

into the guide-ways 17 especially when the same is filled, than is necessary when the barrel must slide on its supporting platform. If desired side frames 11^a may be provided to act as a track or guide for the lower portion 24 of the platform 12 in its travel over the rollers 15, but these members 11^a must, it will be understood, be wide enough apart to permit transverse movement of the upper portion of the platform 12, as the barrel cooperates with the centering guides 17.

Among the advantages of our invention may be enumerated the ease of loading and unloading a container onto the work holding platform 12, and the facility with which the same may be moved into and out of co-operation with the alining yoke 17 due to the disposition of the barrel supporting platform 12 on substantially the same level as the loading platform 11, and to the presence of the rollers 15 and the transversely disposed rollers 25 which reduce friction to a minimum. Since it is possible to roll the barrel onto its carrying platform without lifting the same or without the necessity of inverting it, the container may have its cap or cover applied thereto when the same is filled with substantially the same facility and ease of movement as when empty. The tapered or inclined portions 17^a of the guide-ways are effective to automatically center the container as the same is moved in between the guide-ways. The use of a fixed support or loading step 13 is a noteworthy feature because this permits the barrel to be moved from the rollers into a stationary position by only a small degree of tilting and without the necessity of lifting the barrel independent of its carrying platform. By having the alining yoke co-operate with only the lower portion of the barrel, the upper part thereof is left free to be expandible as the cover is forced into the croze. The construction is rigid and durable and both sets of rollers 15 and 25 are adapted to support the barrel when filled and while a pressure is applied thereto in forcing down the cover.

115
We claim as our invention:

1. The combination with a work centering or alining device, of a work holder movable toward and from the centering device, said work holder comprising a plurality of normally superposed portions, at least one 120 of which is laterally movable with the work relatively to the other by the cooperation of the work with the centering device.

2. The combination with a track, of a work centering device, and a work holder 125 movable along said track toward and from the work centering device, a portion of said work holder being yieldable with and by the work transversely of said track as the work cooperates with said centering device.

3. The combination with a pair of work alining guideways, of a work supporting platform movable toward and from said guide-ways, the latter being adapted to co-
5 operate with the work without engaging said platform, the latter comprising upper and lower portions, the upper of which is adapt-
ed to be moved relative to the lower portion to center the work as the same enters the
10 guide-ways.
4. The combination with a work carrying platform comprising upper and lower por-
tions, of a plurality of wheels for supporting said platform, a pair of work centering
15 guide-ways spaced above the platform, and between which the work is adapted to be moved on the platform, a plurality of wheels transversely disposed with respect to the first mentioned wheels, supporting the up-
20 per portion of said platform on the lower, and means comprising a plurality of springs in cooperation with said upper and lower portions for normally retaining the same in alinement but permitting the upper portion
25 to be moved transversely to the lower as the work enters the guide-ways.
5. The combination with a work holding platform, comprising upper and lower por-
tions, of rollers secured to one of said por-
30 tions and against which the other portion is adapted to slide, a plurality of rollers on which said lower portion is mounted, a pair of leaf springs spaced apart extending in opposite directions, and secured at one end
35 to one of said portions of the platform, a pin secured to the other portion and project-
ing between said springs, and a work centering device located above the platform for cooperation with the work carried on
40 said platform, the upper portion of the plat-
form being transversely yieldable or move-
able when the work enters said centering device.
6. The combination with a work holder, of
45 a plurality of supporting wheels therefor, one of which is movable relatively to the work holder to a position substantially centrally of the longitudinal axis of the work holder and approximately alined with a ver-
50 tical axis through the center of gravity of the work, the work being tilttable on said centrally disposed wheel to a position in which the other supporting wheels are free from the weight of the work and holder, and
55 a support beneath said holder of less height than the tops of the wheels, said support and central wheel being adapted to immovably retain the work and holder in tilted position.
7. The combination with a series of paral-
60 lel rollers, of a work carrying platform, adapted to be carried by and moved over said rollers and a fixed step with a tread of a width equal to about half the length of said work carrying platform, of slightly less
65 height than the tops of the rollers, and dis-
- posed adjacent an end roller of the series, said work carrying platform being movable to a position with its center of gravity over or overhanging said end roller of the series and tilttable on said end roller to a position 70 in which the platform is carried by said step and the end roller.
8. The combination with a plurality of rollers, of a work holder carried by the same, a fixed support of less height than the tops 75 of the rollers adjacent an end roller and a loading platform of substantially the same height as the work holder on the other side of the fixed support from the end roller and spaced a little more than half the length of 80 the work holder from the axis of said end roller, said work holder being tilttable on the end roller to a position where carried by the said end roller and said support.
9. The combination with a plunger down- 85 wardly operable to engage a container, of a yoke adapted to cooperate with said container or center the same with respect to the plunger, and a platform mounted for uni-
versal horizontal movement and on which a 90 container may be placed and moved toward and from the centering yoke and permitted to adjust itself laterally with respect to such yoke.
10. The combination with a pressure oper- 95 ated plunger adapted on downward move-
ment thereof to engage a container, of a guide yoke adapted to cooperate with said container to dispose the same axially of said plunger, and a container supporting plat-
100 form mounted on rollers beneath the plunger for movement to and from the yoke and comprising upper and lower superposed por-
tions, the upper portion of which is yield-
ably secured to the lower to permit trans-
verse movement of the upper on the lower when the container is not moved straight or directly longitudinally into the guide yoke.
11. The combination with a pressure 110 plunger located above a container and adapted on downward movement thereof to engage a container, of a centering device adapted to cooperate with the outside of said container to axially aline the same with said plunger, a plurality of rollers, a container 115 supporting platform disposed beneath the centering device and carried by the rollers toward and from the centering device, a fixed support of less height than the tops of the rollers located adjacent the roller remote 120 from the centering device, a stop on said fixed support extending above the tops of said rollers to approximately the same height as the upper portion of the platform and separated slightly more than half the 125 length of the container platform from the axis of said remote roller, said platform being tilttable on said roller to a position where carried by the same and said support, and comprising upper and lower portions sepa- 130

rated by rollers on which one portion may slide on the other, and a plurality of springs between and in cooperation with said upper and lower portions adapted to maintain said portions in superposed relationship, but adapted to permit the upper portion to yield or move on the lower when the container supported thereby enters said centering device.

10 12. The combination with a plunger adapted to position a cover on a container, of a centering device located beneath the plunger for cooperation with the outside of said container to aline the same with said plunger, a container supporting platform adapted for movement toward and from said centering device on a plurality of wheels about at least one of which said container is tilttable, and a support adapted to immovably carry a portion of the weight of said container platform in tilted position free of some of said wheels.

13. The combination with a work carrying platform comprising upper and lower portions, of a plurality of wheels for supporting lower portion of the platform, a pair of work centering guideways, spaced above the platform and

between which the work is adapted to be moved on said platform, and another plurality of wheels transversely disposed with respect to the first mentioned wheels and supporting the upper portion of the platform.

14. The combination with an element 35 adapted to operate upon a container, and a centering device for positioning a container with reference thereto, of a carrier for presenting the work to the centering device, and a conveyor support and a loading support 40 for the carrier, the latter acting temporarily to retard movement of the carrier when in loading position.

15. The combination with a loading support provided with a pit having rollers 45 therein, an element arranged above said pit and adapted to operate upon a container, and a centering device overhanging the pit to position the container with reference to said element, of a carrier movable on the 50 rollers to present the work to the centering device, said carrier being guided by the walls of the pit.

EUGENE E. COLLAMER.
GEORGE R. COLLAMER.
